UNITED STATES PATENT OFFICE.

EDWARD A. SCHREIBER, OF CHICAGO, ILLINOIS, ASSIGNOR TO VAPOR CAR HEATING COMPANY, INC., OF CHICAGO, ILLINOIS, A CORPORATION OF NEW YORK.

WATER-HEATING APPARATUS.

1,321,131.

Specification of Letters Patent. Patented Nov. 11, 1913.

Application filed October 14, 1918. Serial No. 258,038.

To all whom it may concern:

Be it known that I, EDWARD A. SCHREIBER, a citizen of the United States, residing at Chicago, in the county of Cook and State 5 of Illinois, have invented certain new and useful Improvements in Water-Heating Apparatus, of which the following is a specification.

My invention relates to apparatus for 10 heating water, adaptable particularly for railway cars, and more especially for private cars, so-called, or other railway cars which are likely to be cut off from the steam supply provided by the locomotive or the station 15 steam line.

The primary object of the invention is to 20 provide a water heating apparatus, suitable for railway cars of this general type, which will be relatively simple in its construction 25 and will serve to maintain a supply of hot water for wash basins or other fixtures available for immediate use, whether the car be connected up or not with a locomotive or other source of supply of steam.

The invention consists in the novel arrangements, constructions and devices to be 30 hereinafter described and claimed for carrying out the above stated objects, and such other incidental objects as will appear in the following description.

The invention is illustrated in a preferred embodiment in the accompanying drawings, wherein:

Figure 1 is a diagrammatic view in perspective of an apparatus constructed in accordance with the invention, shown in connection with the flooring and side walls of the car, the latter being illustrated fragmentarily;

Fig. 2 is a front elevation of a stove, which may be used for cooking purposes and serves, in the arrangement constituting my invention, to heat, directly or indirectly, all of the water used in the car at such times as the car may be disconnected from the source of supply of steam.

Fig. 3 is a side elevation of the local heating unit, on a smaller scale, showing, partly in section and partly in elevation, certain tanks and piping forming part of the water heating apparatus of my invention;

Fig. 4 is a longitudinal sectional view of a preferred form of steam heating device;

Figs. 5 and 6 are cross-sectional views on lines 5-5 and 6-6, respectively, of Fig. 4;

Fig. 7 is a longitudinal sectional view of a vapor regulator for controlling the supply of steam to the steam heating device; and

Fig. 8 is a plan section on line 8-8 of Fig. 7.

Like characters of reference designate like parts in the several figures of the drawings.

Referring to the drawings, and particularly to the diagram shown in Fig. 1, 10 indicates in outline the flooring of the car, 11 the usual steam train pipe which extends lengthwise of the car under the flooring, and 12 a water supply tank, the contents of which are kept under air pressure by means of a pipe 13 which is connected with the air 70 train line (not shown). 14 is a water outlet pipe leading from tank 12. From this pipe leads a cold water service pipe 15 provided with branch pipes 16, connected with cold water faucets or other fixtures requiring cold 75 water. Pipe 14 has a connection 17 leading to a steam heating device 18 (Figs. 4, 5 and 6), and 19, 19^a, 19^b is a hot water service pipe provided with branch pipes 20 leading to faucets or other fixtures requiring hot 80 water, the return end 19^b of this circuit being connected by a T 21 with pipe 14 and the pipe connection 17 above mentioned. This circuit includes, in addition to the pipes just mentioned, a pipe coil 22 and an ex- 85 pansion tank 23. The pipe coil 22 is arranged within an expansion tank 24, connected by pipes 25, 26 with the water back 27 of a stove or local heater 28. The apparatus shown in the drawings is intended to be used 90 particularly upon a private car, so called, and the stove 28 in such case is a cooking range. Water is supplied to the water back 27 of the stove 28 from tanks 29 provided with a stand pipe 30 which would ordinarily 95 extend through the roof of the car. The cold water pipe 15 is connected at 31, 31 with tanks 29, the end of pipe 15 being connected with the expansion tank 24, as shown. Water from pipe 15 will pass into tanks 100 29, a check valve 32 being arranged in the pipe in advance of the tanks. Water will flow from the tanks by gravity into the expansion chamber 24, and thence to the water back 27, as required. 33 is a 105 pipe leading from the expansion tank 24 by means of which hot water may be drawn from this tank for use in the kitchen. 34 is a check valve in pipe 14 between pipe 15 and the T 21.

The steam heating device 18 consists preferably of a cylindrical shell 35 on the ends of which are screwed heads 36, 37, into which are tapped the pipes 17, 19, respectively. A pipe 38, 38^a leads from the train pipe 11 to and through the steam heating device, the end of pipe section 38^a passing loosely through the head 37 and being screwed into a boss 39 formed on the head 36. The head 37 is formed with a threaded boss 40. Between this boss and the pipe 38^a is arranged suitable packing 41, held in place by follower 42 and nut 43. Screwed into the outer end of the boss 39 of head 36 is a pipe 44 which leads to the thermostat chamber 45 of the vapor regulator 46 which is arranged between pipe sections 38 and 38^a, above mentioned. This vapor regulator, shown in Figs. 7 and 8, may be of the same general construction as that patented in patent to Egbert H. Gold, No. 771,628, dated October 4, 1904, and need not be described in detail. The vapor regulator serves to maintain the steam passing through the steam heating device at substantially atmospheric pressure; that is to say, steam from pipe 38 will pass through port 47 and through strainer 48 into pipe section 38^a, so long as the thermostat 49 remains unexpanded, and valve 50 stands away from its seat 51. If steam is introduced into the heating device in greater volume than can be contained therein, the excess passing through the thermostat chamber through pipe 44 will expand thermostat 49 and seat the valve. In an ordinary operation the port 47 of the vapor regulator is throttled to the extent necessary to maintain the amount of steam required for the heater.

Operation: When the train pipe 11 of the car is supplied with steam from a locomotive or other source of supply, water forced from the tank 12 by air pressure supplied from the branch air line 13, is heated in the steam heating device 18 and circulates through the circuit made up of pipe 19, coil 22 and pipe 19^a, expansion tank 23, and pipe 19^b. The water thus heated may be drawn off or otherwise used at the fixtures (not shown) connected with branch pipes 20. If there is no fire in stove 28, the water in passing through the coil 22 will heat or warm the water in tank 24. Pipe 15 supplies water from tank 12 to the cold water faucet or other fixtures connected with branch pipes 16. The same pipe supplies water to the tanks 29 which replenish the water in tank 24 and the water back 27 of the stove. If the car is cut off from the locomotive, a fire may be lighted in the stove 28. This will heat the water in the water back 27, producing circulation between the water back and expansion tank 24. Water in tank 24 will heat the water in coil 22, so that the fixtures associated with branch pipes 20 are

kept supplied with hot water. It will be observed that the hot water which goes to these fixtures is kept in constant circulation whether it receives its heat from the steam heating device or from the expansion tank 70 connected with the stove, so that hot water can be drawn at once from any of the aforementioned fixtures without waste. Preferably the discharge pipe 44 from the steam heating device passes around the tank 12, 75 and the steam heating device itself with the steam pipe leading thereto is located close to the tank 12; the tank heater and associated pipe connections may be inclosed in an insulated box, the arrangement being 80 generally similar to that described in my Patent No. 1,249,518, granted December 11, 1917.

It will be obvious that the steam heating device and the stove may be used at the same time if found desirable. The vapor regulator serves to supply the water heater with just enough steam to keep the water at the desired temperature. A certain amount of steam will always pass through the circuit formed by pipe 38^a, steam heater 18, and pipe 44, to keep the tank and associated parts inclosed within the box 52 from freezing.

I claim:

1. In combination with a railway car having a train pipe adapted to be supplied with steam, of a local water heater of the stove type, a water circulating supply system, a steam heating device adapted to receive 100 steam from the train pipe for imparting heat to the water circulating supply system, and a water heating device forming part of said water circulating supply system arranged so that it will receive heat from the 105 water in the local water heater.

2. In combination with a railway car having a train pipe adapted to be supplied with steam, of a local water heater of the stove type, a water circulating supply system, a steam heating device adapted to receive 110 steam from the train pipe for imparting heat to the water circulating supply system, and a water heating device forming part of said water circulating supply system provided with a water space not in communication with the water space of the local water heater, but arranged so that it will receive heat from the water in said local water heater.

3. In combination with a railway car having a train pipe adapted to be supplied with steam, of a local water heater of the stove type, a water circulating supply system, a steam heating device adapted to receive 125 steam from the train pipe for imparting heat to the water circulating supply system, means for maintaining steam in said steam heating device at a substantially constant temperature regardless of changes of pres- 130

- sure in the train pipe, and a water heating device forming part of said water circulating supply system arranged so that it will receive heat from the water in said local 5 water heater.
4. In combination with a railway car having a train pipe adapted to be supplied with steam, of a local water heater of the stove type, a water circulating supply system, a 10 water supply tank for the circulating supply system, and means for maintaining the water therein under air pressure, a steam heating device adapted to receive steam from the train pipe for imparting heat to the water 15 circulating supply system, and a water heating device forming part of said circulating supply system arranged so that it will receive heat from the water in the local water heater.
- 20 5. In combination with a railway car having a train pipe adapted to be supplied with steam, of a stove having a water heating space and an expansion tank connected therewith, a water circulating system, a portion 25 of which is arranged so as to receive from or impart heat to the fluid in said expansion tank, and a steam heating device adapted to receive steam from the train pipe for heating the water in said circulating 30 system.
6. In combination with a railway car having a train pipe adapted to be supplied with steam, of a stove having a water heating space and an expansion tank connected 35 therewith, a water circulating system, a portion of which is arranged to receive heat from the fluid in said expansion tank, and a steam heating device adapted to receive steam from the train pipe for heating the 40 water in said circulating system.
7. In combination with a railway car having a train pipe adapted to be supplied with steam, of a stove having a water heating space and an expansion tank connected 45 therewith, a water circulating system, a portion of which is arranged to receive heat from the fluid in said expansion tank without communicating therewith, and a steam heating device adapted to receive steam from 50 the train pipe for heating the water in said circulating system.
8. In combination with a railway car having a train pipe adapted to be supplied with steam, of a stove having a water heating space and an expansion tank connected 55 therewith, a water circulating system comprising a pipe coil located within and adapted to receive heat from the fluid in said expansion tank, and a steam heating device adapted to receive steam from 60 the train pipe for heating the water in said circulating system.
9. In combination with a railway car having a train pipe adapted to be supplied with 65 steam, of a stove having a water heating
- space and an expansion tank connected therewith, a water circulating system comprising a pipe coil located within and adapted to receive heat from the fluid in said expansion tank, and a steam heating 70 device adapted to receive steam from the train pipe for heating the water in said circulating system, said circulating system comprising also an expansion tank arranged above said pipe coil. 75
10. In combination with a railway car having a train pipe adapted to be supplied with steam, of a stove having a water heating space and an expansion tank connected therewith, a water circulating system, a portion 80 of which is arranged so as to receive or impart heat to the fluid in said expansion tank, a steam heating device adapted to receive steam from the train pipe for heating the water in said circulating system, a water 85 tank and means for maintaining the contents thereof under air pressure for supplying water to said circulating system, a water tank to supply water to the water heating space of the stove, and a pipe connecting 90 said last-named tank with the first-named tank.
11. In combination with a railway car having a train pipe adapted to be supplied with steam, of a local water heater of the 95 stove type, a water circulating system, and a steam heating device adapted to receive steam from the train pipe for imparting heat to the water circulating system; said water circulating system being arranged so 100 that it will receive heat from or impart heat to the water in the local water heater and constructed so as to provide an endless circuit for the continuous circulation of water.
12. In combination with a railway car 105 having a train pipe adapted to be supplied with steam, of a local water heater of the stove type, a water circulating system, and a steam heating device adapted to receive steam from the train pipe for imparting heat 110 to the water circulating system; said water circulating system being arranged so that it will receive heat from or impart heat to the water in the local water heater, and constructed so as to provide an endless circuit 115 having no communication with the water space of the local water heater for the continuous circulation of water.
13. In combination with a railway car having a train pipe adapted to be supplied 120 with steam, of a local water heater of the stove type provided with a water space having a draw-off pipe and with means for introducing a fresh supply of water into said water space as water is drawn therefrom, a 125 water circulating system, and a steam heating device adapted to receive steam from the train pipe for imparting heat to the water circulating system which is arranged so that it will impart heat to or receive heat from 130

- 4 the water in said local water heater, and
constructed so as to provide an endless cir-
cuit for the continuous circulation of water.
- 5 14. In combination with a railway car
having a train pipe adapted to be supplied
with steam, of a local water heater of the
stove type provided with a water space
having a draw-off pipe and with means for
10 introducing a fresh supply of water into
said water space as water is drawn there-
from, a water circulating system, and a
steam heating device adapted to receive
steam from the train pipe for imparting heat
15 to the water circulating system which is
arranged so that it will impart heat to or
receive heat from the water in said local
water heater, and constructed so as to pro-
vide an endless circuit having no communica-
20 tion with the water space of said local
water heater for the continuous circulation
of water.
- 25 15. In combination with a railway car
having a train pipe adapted to be supplied
with steam, a stove in the car provided with
a water space having a draw-off pipe, a
water supply tank and means for maintain-
30 ing the contents thereof under air pressure,
a pipe leading from said tank to the water
space of the stove, a steam heating device
adapted to be supplied with steam from the
train pipe and with water from said supply
35 tank, and a hot water circulating system
comprising a water heating element ar-
ranged to receive heat from the water in the
water space of the stove, a pipe connecting
said steam heating device with the said water
40 heating element, and a return pipe connect-
ing the water heating element with said
steam heating device.
- 45 16. In combination with a railway car
having a train pipe adapted to be supplied
with steam, a stove in the car provided with
a water space having a draw-off pipe, a
water supply tank and means for maintain-
50 ing the contents thereof under air pressure,
a pipe leading from said tank to the water
space of the stove, a steam heating device
adapted to be supplied with steam from the
train pipe and with water from said supply
55 tank, and a hot water circulating system
comprising a water heating element ar-
ranged to receive heat from the water in the
water space of the stove, a pipe connect-
ing said steam heating device with the said water
60 heating element, a return pipe connect-
ing the water heating element with said
steam heating device, the water space of the
stove comprising an expansion tank, and an
expansion tank being arranged in said re-
turn pipe.
- 65 17. In combination with a railway car
having a train pipe adapted to be supplied
with steam, a stove in the car provided with
a water back and with an expansion tank ar-
ranged above and connected with the water
70 back, a water supply tank provided with
means for maintaining the contents thereof
under air pressure, a pipe leading from said
water supply tank to said expansion tank,
a gravity supply tank connected with said
75 pipe at a point above the expansion tank
and provided with a stand pipe, a steam
heating device adapted to receive steam
from the train pipe and water from said
supply tank, a hot water circulating system
80 comprising a pipe coil arranged in said ex-
pansion tank, a pipe leading from the steam
heating device to said pipe coil, an expansion
tank arranged above the first-named ex-
pansion tank, a pipe leading from said water
85 coil to said last-named expansion tank, and
a pipe leading from the last-named ex-
pansion tank back to said steam heating device.

EDWARD A. SCHREIBER.
